No. 767,870.

PATENTED AUG. 16, 1904.

W. M. CONRAN.
EMERGENCY FIRE SCREEN.

APPLICATION FILED MAR. 5, 1904.

NO MODEL.

UNITED STATES PATENT OFFICE.

WILLIAM MASSEY CONRAN, OF MARSHALLTOWN, IOWA.

EMERGENCY FIRE-SCREEN.

SPECIFICATION forming part of Letters Patent No. 767,870, dated August 16, 1904.

Application filed March 5, 1904. Serial No. 196,639. (No model.)

To all whom it may concern:

Be it known that I, WILLIAM MASSEY CONRAN, a citizen of the United States, and a resident of Marshalltown, in the county of Marshall and State of Iowa, have invented a new and Improved Emergency Fire-Screen, of which the following is a full, clear, and exact description.

My invention relates to a fire-screen adapted for the purpose of extinguishing fires and capable of general use, but especially useful in theaters and other buildings in which a stage is employed.

Presuming that the wall carrying the proscenium-arch is of fireproof construction, my invention is intended to protect the proscenium-opening of a stage and to effectually and instantaneously eliminate the danger of fire passing from the stage to the auditorium, and it is also designed to prevent or modify the effect of gases reaching the audience in the case of an explosion on the stage.

Reference is to be had to the accompanying drawings, forming a part of this specification, in which similar characters of reference indicate corresponding parts in all the figures.

Figure 1 is a sectional view of the front part of a stage, showing the fire-screen and rear of the stage in perspective. Fig. 2 is a view of a detail; and Fig. 3 is a cross-section of the arch-covering, showing the position of the conductors for water.

In the drawings, 1 represents a stage having a proscenium 2 and an arch 3. 4 4 represent water-pipes provided with perforations 5 5, which are preferably located along the walls of the arch and along the floor. They may extend out from the walls or be flush with their surface. These pipes are supplied by 40 means of a siamese coupling 6, connected to a supply-pipe 7, having a stop-cock operated by a lever 8 and a valve 9. It is intended to connect with a main 10, a cut-off valve 11 being provided near the main operated by mechanism 12 from the street, so that the whole device may be within the control of the fire department. The walls of the arch are preferably covered with steel 13, which may be protected on one or both sides by asbestos 14,

as shown. The footlight-trough 15 is a convenient trough for the reception of the water which may flow down the stage and is provided with a hole 16, connected to a system of piping for conducting the water to a waste-pipe.

In the drawings a double system of water-pipes 4 is shown, which may take the place of the columns or pillars on the inner and outer edges of the arch. The perforations are preferably placed in the position indicated in Fig. 2—that is, in staggered relation and from one to two inches apart, with a double row of holes of different sizes, according to the conditions existing. When the pipes are put under water-pressure, they will discharge, so as to form a double screen of water across the proscenium-arch, the water being thrown through each pipe directly across or vertically to the opposite pipe and every jet throwing to the opposite side in a straight line, thus forming a network of water which will prevent the passage of flame.

The valve 9 is intended to be kept closed except during show time, when pressure is put on the valve operated by the lever 8, so as to give instant operation in case of fire by operating the lever 8. The service-pipe 7 is in direct communication with the main 10 or other water-supplying device, and the cut-off valve 11 is provided in order that the fire department may have entire control of the system after arriving, so that they can cut off the fire-screen at once, if desired, in order to stop the waste of water or for any other purpose. Either one of the pipes 4 4 may be flushed out for the purpose of cleaning away any accumulation of dust by slightly opening the valve 9 while the cock 8 is open through a trap on the lower edge of the stand-pipe. (Not shown.)

This device may be operated automatically, if required, and can be worked from a tank on the roof or a specially-made chemical-tank, where water-pressure is not available. It may also be operated from either side or from both sides, or from any desired point, or even from the outside by means of a wire rope connected through pulleys to the lever 8.

This invention may be applied in other

places than in theaters, and in case of use in theaters it is intended to be also used on the doors from the stage to the auditorium, when they exist.

5 It will be seen that by the use of this fire-screen the cumbrous and heavy steel and iron curtains, whether vertically or horizontally sliding, are done away with. These curtains when vertically lifted weigh from ten to twenty tons, which weight is nearly doubled by the counterweight required, which makes them a dangerous device to keep suspended from the upper walls. They are difficult to work and liable to get out of order at critical moments. It is a hard matter to keep them level, and they are exceedingly difficult to make and operate and cannot be rapidly brought into position for protection in case of fire. They are also a hindrance to fire-fighting, because they cut off all escape through the proscenium-arch and make an impassable barrier which prevents the passage of the firemen and the fire apparatus through the proscenium-arch.

25 By the use of my device all these troubles are avoided. Persons may easily pass from one side to the other without hindrance, and the fire department can pass a large stream of water directly through the screen without interfering with its action in any way. If desired, small nozzles may be placed in the perforations 5 in order to direct the stream directly across the opening. The spray or random distribution is of no use in a construction

of this kind, and it is better to have the streams 35 go directly across.

It will be understood that the water-pressure is always intended to be on the valve 9, and it is only intended to proceed as far as the lever 8 during show time.

40 This invention is especially valuable for the protection of élévator - hatchways, entirely preventing the possibility of flame or gas rushing up the shaft. The application in this case would be around the hatchway, let into the 45 construction, or attached to the ceiling just under the hatch or on the floor above. Single or double screens may be used, as may be preferred, and the elevators may continue to run while the screen is in operation.

50 Having thus described my invention, I claim as new and desire to secure by Letters Patent—

1. A fire-extinguishing device for theater-stages having a plurality of parallel endless perforated vertical conductors, and a supply-pipe therefor having a stop-cock and a valve.

2. A fire-extinguishing device for stages comprising a plurality of vertical parallel perforated endless conductors, and a supply-pipe therefor.

60 In testimony whereof I have signed my name to this specification in the presence of two subscribing witnesses.

WILLIAM MASSEY CONRAN.
